R. W. ROSENDAHL.
SAFETY RAZOR BLADE SHARPENING DEVICE.
APPLICATION FILED APR. 23, 1910.

967,977.

Patented Aug. 23, 1910.

2 SHEETS—SHEET 2.

UNITED STATES PATENT OFFICE.

REYNOLD W. ROSENDAHL, OF PHILADELPHIA, PENNSYLVANIA.

SAFETY-RAZOR-BLADE-SHARPENING DEVICE.

967,977.

Specification of Letters Patent. Patented Aug. 23, 1910.

Application filed April 23, 1910. Serial No. 557,178.

To all whom it may concern:

Be it known that I, REYNOLD W. ROSENDAHL, a citizen of the United States, residing at Philadelphia, in the county of Philadelphia and State of Pennsylvania, have invented certain new and useful Improvements in Safety-Razor-Blade-Sharpening Devices, of which the following is a specification.

10 My invention relates to improvements in safety razor blade sharpening devices, the object of the invention being to provide improved means whereby the safety razor blade may be both honed and stropped so that blades heretofore discarded may be used again and again after sharpening the same.

15 A further object is to provide a device of this character which is extremely simple in construction, cheap to manufacture, which may be easily manipulated by anyone of average intelligence to quickly sharpen the blade, which is neat and attractive in appearance, and strong and durable in use.

20 With these and other objects in view, the invention consists in certain novel features of construction and combinations and arrangements of parts, as will be more fully hereinafter described and pointed out in the 25 claims.

In the accompanying drawings: Figure 1, is a reduced plan view illustrating my improvements. Fig. 2, is a plan view of my honing mechanism. Fig. 3, is a view in 30 longitudinal section of the same. Fig. 4, is a view in elevation of the right hand end of Fig. 2. Fig. 5, is a view in section on the line 5, 5, of Fig. 2. Fig. 6, is a view in section on the line 6, 6, of Fig. 2. Fig. 7, 35 is a view in end elevation of the left hand end of Fig. 2. Fig. 8, is a perspective view of the razor blade holder partly dismantled. Fig. 9, is a perspective view of the separable section of the razor blade holder. Fig. 10, 40 is a view of an ordinary safety razor blade, and Fig. 11, is a view of one of the sliding sleeves used on the razor blade holder.

45 My improved device comprises both a honing mechanism illustrated at 1, and a strop 2, which are connected by a bail 3, the strop being secured around the intermediate portion of the bail, and having a perforation 4 at one end, which may be caught over a hook or other suitable device (not shown) 50 so that the strop may be held taut while the razor is being stropped thereon.

The honing mechanism 1 comprises two parallel stone holders 5, 5, and these stone holders are rigidly connected at one end by two cross bars 6, 6, so that they are maintained a uniform distance apart and in perfect parallelism. Each stone holder comprises a rectangular tubular casing disposed with their angular portions adjacent each other. These stone holders have their inner 60 adjacent walls cut away so as to expose two faces of the stones 7, which are securely held in the holder. While I refer to these parts 7 as stones I would have it understood that I am in nowise limited to the 65 particular material employed as any composition which is efficacious as a honing medium, may be employed and the manner of assembling the stones in the holders may also be varied at will, except that the stones 70 must be rigidly held so that they will have no longitudinal or lateral movement in the holders, and will be positioned with their edges adjacent each other. Each of these 75 stone holders 5 at one end, is provided with an eye 8 in which the ends of bail 3 are positioned while the other ends of the 80 holders have ornamental knobs 9 thereon.

Between the holders and rigidly secured in the bars 6, 6, is a guide sleeve 10 through 85 which my improved razor blade holder 11 projects, and is adapted to be reciprocated and intermittently oscillated. The holder 11 comprises a rod having a hand-hold 12 at one end, and its other end is cut out as shown 90 at 13 and provided with a removable section 14 to fit this cut out portion, the rod having lugs 14^a, which are adapted to project through the end openings 15 in the ordinary safety razor blade 16, and then 95 into recesses 17 in the removable section 14, so as to hold the razor blade against lateral as well as longitudinal movement.

18 and 19 represent sleeves which are adapted to slide on the rod, and each of 100 these sleeves is provided with slots 20 in opposite sides to receive the ends of the razor blade, and yet permit the sleeves to slide over the removable section 14, and securely hold the section 14 and the razor 105 blade to the blade holder.

When the blade is secured in the holder, the holder is entered from the open end of the honing mechanism and the handle end 12 is passed through the sleeve 10.

To hone the blade, the operator grasps 110 the honing mechanism in one hand, and with

the other he reciprocates the blade holder and intermittently oscillates the same or in other words, gives a partial turn to the holder.

- 5 It will be observed particularly by reference to Fig. 5, that when the blade holder is in one position, the opposite cutting edges of the razor blade will be engaging the upper and lower faces respectively of the 10 two stones, so that when the holder is moved longitudinally, these surfaces of the blade in contact with the stones will be acted upon by the stones, and when the holder is given a partial turn, the opposite faces of the two 15 stones will be engaged by the opposite faces of the two razor blade edges, so that by intermittently oscillating the holder and continuously reciprocating it as long as is necessary to impair the proper cutting edge 20 to the blade, both edges of the blade will be presented to the stones at both sides, so that both cutting edges of the blade will be honed.

When the blade has been sufficiently honed, the holder is removed from the honing mechanism, and the blade stropped on 25 the strop 2 in the usual manner, save that he grasps the holder and manipulates the blade by means thereof so as to hone the several edges of the blade.

30 It will thus be seen that with my improvements, the razor blades may be quickly positioned in the holder and both honed and stropped, thus permitting the blades to be utilized over and over again after each 35 sharpening operation.

A great many slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention what 45 I claim as new and desire to secure by Letters Patent is:

1. A sharpening device for double edged blades, comprising parallel hones, and means for moving a double edged blade longitudinally of the hones with each cutting edge of the blade in contact with a hone, substantially as described.

2. A sharpening device for double edged blades, comprising two stationary hones, angular in cross section and disposed with angular edges adjacent each other, and means for moving a double edged blade longitudinally of the hones with each cutting edge

of the blade in contact with the hone, substantially as described.

3. A sharpening device for double edged blades, comprising two stationary hones, angular in cross section and disposed with angular edges adjacent each other, means for moving a double edged blade longitudinally of the hones with each cutting edge of the blade in contact with the hone, and said means adapted to be oscillated whereby the opposite sides of the blade are presented to the hones, substantially as described.

4. A device of the character described comprising parallel hones, rectangular in cross section and disposed with angular edges toward each other, and means for moving the razor blade in simultaneous contact with both of said hones, substantially as described.

5. A device of the character described comprising parallel hones, and a razor holder constructed and adapted to be reciprocated and oscillated whereby both cutting edges of the razor blade have both sides presented to the hones, substantially as described.

6. A device of the character described comprising two parallel hones, each hone angular in cross section, each having two honing surfaces at an angle to each other, a guide between said hones, and a razor blade holder movable in said guide and constructed and adapted to be reciprocated and intermittently oscillated, substantially as described.

7. A device of the character described comprising parallel hones, each hone angular in cross section and having its honing surfaces at an angle to the other, bars connecting the hones at one end, a guide sleeve fixed in said bars between said hones, and a razor blade holder removably mounted in said guide sleeve, substantially as described.

8. A device of the character described comprising parallel hones, rectangular in cross section and disposed with angular edges adjacent each other, bars connecting the hones at one end, a guide sleeve fixed to said bars between the hones, and a razor blade holder removably mounted in said guide sleeve, substantially as described.

In testimony whereof I have signed my name to this specification in the presence of two subscribing witnesses.

REYNOLD W. ROENDAHL.
